UNITED STATES PATENT OFFICE.

ABRAHAM E. CHERNACK, OF BOSTON, MASSACHUSETTS.

MACHINE FOR CUTTING NOZZLES FOR TURBINES AND THE LIKE.

No. 927,450.

Specification of Letters Patent.

Patented July 6, 1909.

Application filed May 13, 1908. Serial No. 432,657.

To all whom it may concern:

Be it known that I, ABRAHAM E. CHERNACK, a subject of the Emperor of Russia, and a resident of Boston, in the county of 5 Suffolk, in the State of Massachusetts, have invented certain new and useful Improvements in Machines for Cutting Nozzles for Turbines and the Like, of which the following is a specification.

10 My invention is particularly designed for use in cutting or broaching out the nozzle holes of steam turbines, which holes are tapering and of irregular cross-section at different points in their length, but my invention is also applicable to the cutting of 15 tapering holes for any purpose.

In the accompanying drawings Figure 1 is a front elevation of a machine embodying my invention; Fig. 2 is a side elevation 20 partly in section; Fig. 2^a is a plan view of a rocking lever; Fig. 3 is a sectional view showing a suitable operating mechanism; Fig. 4 is a sectional diagrammatic view; Fig. 5 is a cross section through the finished 25 nozzle hole at 5—5, Fig. 4; Fig. 6 is a cross-section at 6—6, Fig. 4; Fig. 7 is a face view of the outlet end of the nozzle at 7—7, Fig. 4; Figs. 8 and 9 are cross-sections of the 30 cutting tools and expanding wedge corresponding with Figs. 5 and 6, respectively; and Fig. 10 is a sectional view of a modification.

My invention will be better understood if I first explain the peculiar shape of nozzle holes in steam turbine rings, for the cutting of which my machine is especially designed. Fig. 4 is a diagrammatic section through a portion of turbine ring at one of the nozzle holes in process of formation. At the entrance end for the steam is a hemispherical hole *a*, whence the passage or nozzle leads diagonally at *y*, gradually increasing in cross-section, and gradually changing from a round at 5—5 to a round cornered rectangle at 6—6 and 7—7. In the formation of these nozzle holes a cylindrical hole is first drilled or otherwise formed through the center line of the desired nozzle and the cup *x* is formed, and then by means of my 45 machine, which I will now describe, I cut out the hole to the irregularly shaped taper indicated by the views, Figs. 4 to 7, the dotted cross hatching in Fig. 4 indicating the metal which has to be cut away in this 50 operation.

The essential working elements of my machine are one or more reciprocating cutting tools and a movable backing member for expanding the cutting tool or tools against the wall of the hole, said backing member 60 presenting a bearing face to the cutter tapering or inclined to the line of movement of the backing member, and means for reciprocating the latter between the cutting strokes. By preference I employ two such cutters to 65 broach out the opposite sides of the hole at the same time, and for the expanding means I preferably use a tapering wedge between the two cutters and means for intermittently reciprocating that wedge to press the two 70 cutters outwardly during their cutting stroke, and free them on the return stroke.

Referring to Figs. 1, 2 and 3, A and A¹ are the two reciprocating cutters which are shown as depending vertically (Fig. 2) and 75 are carried by two tool carriers, 17, 17, adapted to slide upon two dovetailed upright guides 18. These guides are in turn mounted upon two horizontal slides 20 in dovetailed guides 23 (Fig. 2) in the standard or frame S, and the slides 20 are normally pressed toward each other by flat springs 24 (Figs. 1 and 2). The guides 18 are so mounted as to be angularly adjustable (Fig. 1) on the slides 20, as by pivoting the 80 guides at their lower ends 25 and having lugs 26 at their upper ends with curved slots 27 through which pass securing screws 28. By this means the two cutters A and A¹ may be set at a suitable angle to each other depending upon the taper of the hole to be 85 cut, and the tapering of the wedge piece B between the two cutters will also correspond. To keep the cutters and wedge piece in the same plane, it is preferable to make their 90 meeting faces of slightly V-section, at least at some parts (Figs. 8 and 9).

The expanding wedge piece B is removably attached at its upper end to a block 29 reciprocating in a guide 30 on the top of the 100 frame of the machine.

While variously constructed mechanism may be employed for actuating the cutters A, A¹ and expansion piece B, I have shown in the drawings certain devices which may be employed for the purpose. Thus each slide 17 may be connected by links 16, universally jointed, to the forked end of a rocking lever 12, (Fig. 2^a) which is pivoted at 105 13 to posts on the top of the frame of the 110

machine. The rear of the rocking lever 12 is connected by a rod 11 (Fig. 2), to a crank pin 10 on a disk 9 (Figs. 2 and 3). This disk 9, which also serves as a cam to actuate the expansion piece B, is driven by suitable gearing from the driving shaft *a* with fast and loose pulleys, 1, 2. This gearing may comprise a pinion 5, on the driving shaft, a gear 6, on countershaft 4, pinion 7 and gear 8, which last is secured to the disk 9 or the shaft which carries it.

The cam outline of the disk will be seen on reference to Fig. 2 and it is arranged to act on an antifriction roller on the end of a bell-crank lever 31 pivoted to the frame and connected by a rod 32 (Fig. 2), to one end of a rocking lever 33. A suitable spring 35 may be provided to act in opposition to the cam. The rocking lever 33, which is pivoted to the frame at 14, is pivotally connected at 34 to the block 29 carrying the expansion piece B. The parts are so timed in their operation that while the cutters A and A¹ are descending, or in other words on their return stroke, the expansion piece B is held in its upper position, and the cutters are then more or less free of the work. Just as the cutters are about to begin their upstroke, which is the cutting stroke, the wedge piece B descends to its lower position and thereby forces the cutting edges of the tools outward into cutting engagement with the walls of the metal. The teeth of the cutters are set to cut on the upstroke of the tools. When the cutters have reached the top of their stroke the wedge piece is caused to ascend again to its upper position, to free the cutters.

The work table F may be provided with any well known or suitable feed to be actuated by hand or automatically. In the drawings, for the sake of illustration, the work table F is shown as mounted to be adjustable horizontally upon a plate E, which in turn can be adjusted vertically on guides E¹ on the frame to feed the work up to the cutting tools, by means of a suitable feed screw D.

In the case of working on sections of rings for steam turbines, a special work holder C, Fig. 1, is provided to support the work W at the desired angle. I prefer to make the blank W with butts *w*, Fig. 1, where the nozzles are to be cut out, so as to give a substantially equal support to the two cutters A, A¹, while cutting out the hole, but the butt thus left can be planed off afterward.

The cutting edges of the two cutters are semi-circular toward their forward ends, and generally merge into rectangular outline, as will be understood by reference to Figs. 8 and 9, but this change in cross section is not the same in the two cutters, because it will be seen from Fig. 4 that one side (the short

side) of the finished nozzle hole has a quicker inclination than the other, and the two tools must be shaped accordingly. I do not however confine myself to any particular shape of cutting tools. In fact to cut out one hole, different cutters may be employed, as for example, a pair of cutters with rounded cutting faces to give the general tapering form to the hole, and then another pair of cutters may be substituted for them to finish the rectangular corners of the larger end of the hole. So also, I do not confine myself to the use of a pair of cutters. For example, with large tapering holes, as many as four cutters A², A², (Fig. 10) may be employed with an intermediate expansion or wedge piece B¹ having the section of a cross.

I claim as my invention:

1. A machine for cutting out tapering holes, comprising a cutter and means for reciprocating it, in combination with a movable backing member for the cutter presenting a bearing face to the cutter inclined to the line of movement of the backing member and means for reciprocating the latter between the cutting strokes.

2. A machine for cutting out tapering holes, comprising a pair of cutters and means for reciprocating the same, in combination with a movable intermediate backing member for the cutters presenting bearing faces to the cutters inclined to the line of movement of the backing member and means for reciprocating the latter between the cutting strokes.

3. A machine for cutting out tapering holes, comprising a cutter and means for reciprocating it, in combination with a movable backing member for the cutter presenting a bearing face to the cutter inclined to the line of movement of the backing member, means for reciprocating the latter between the cutting strokes, and means for feeding the work to the cutter.

4. A machine for cutting out tapering holes, comprising a pair of cutters and means for reciprocating the same, in combination with a movable intermediate backing member for the cutters presenting bearing faces to the cutters inclined to the line of movement of the backing member, means for reciprocating the latter between the cutting strokes, and means for feeding the work to the cutters.

5. A machine for cutting tapering holes, comprising a pair of cutters and their carriers and angularly adjustable guides for the latter, in combination with means for reciprocating said cutter carriers, a wedge piece between the cutters and means for intermittently reciprocating the wedge piece, substantially as described.

6. A machine for cutting tapering holes, comprising a pair of cutters and their carriers, angularly adjustable guides for the

latter, a pair of slides on which said guides are mounted, and springs to press the slides toward each other, in combination with means for reciprocating the cutter carriers, a wedge piece between the cutters and means for intermittently reciprocating the wedge piece.

In testimony whereof I have signed my name to this specification, in the presence of two subscribing witnesses.

ABRAHAM E. CHERNACK.
